CLIP PIN

Edmund T. Sommer, Jr., Arlington, Va.

Application August 28, 1947, Serial No. 771,041

2 Claims. (Cl. 24—161)

1

This invention relates to fastening means and particularly to fastening means of the clip type adapted for clipping or pinning together one or more folds of fabric, textile, paper, or the like.

My invention is an improvement in an art in which there are literally hundreds of prior patents none of which so far as I am aware combine the features of unitary production from a single piece of stock, positive locking means, one or more pins adapted to pierce and securely hold the folds of material to be retained, and a positive guard or shield to protect the user or wearer from injury due to the points of the pins. More specifically, I have provided a clip or fastening device of which all elements may be stamped out of a single blank of spring steel or light metal. Moreover, in my device there is a roughly U-shaped recess between the inner and opposed surfaces of two main faces, and with respect to the orientation of said U-shaped recess, an additional inverted recess between the outer surface of one of the main faces and an integral shield member formed as a folded over extension of said main face. This second recess is adapted to receive one or more sheets or folds of material which will be held in place by being pierced by the pin or pins, the points of which lie under and are protected by said overlapping shield member. The open ends of the two main faces are associated with a positive lock adapted to close and secure the otherwise open end of the U-shaped recess.

While my invention may be adapted for a plurality of uses as will more fully be set forth hereinafter, it has for one of its objects, the provision of a clip or fastening device which may be used with safety in fastening diapers on infants. Such use obviously requires the provision of a clip or pin which may be easily fastened or unfastened at will on a squirming infant, yet at the same time will remain securely in place during use with no danger of either becoming unfastened due to movements of the infant or of scratching or otherwise injuring the infant when in use.

My invention has for a further object the provision of a clip or pin which may be used as a garment clasp or costume jewelry on women's apparel or as a tie or suspender clasp by men. My device or clasp may also be used for pinning blankets or bed covering on young children. It may also be used as a paper clip for securing bundles of related papers firmly and intact.

Another object of my invention is the provision of a pin or clip which may be simply stamped from sheet metal, may be readily bent

2

and folded into shape by machine operation and therefore is susceptible to economic production by mass production methods. At the same time it is adapted for decoration by plating with precious metal or engraving or embossing or by anameling or lacquering or by the attaching of separate decorative elements where the production of a more attractive device for outward appearance is desired.

Further objects and advantages of my invention will develop as the description thereof proceeds and the novel features of my invention will be further described in the specification and thoroughly pointed out in the claims.

15 Referring to the accompanying drawing wherein like reference numerals refer to the same or similar elements:

16 Referring to the accompanying drawing wherein like reference numerals refer to the same or similar elements:

17 Referring to the accompanying drawing wherein like reference numerals refer to the same or similar elements:

18 Figure 1 is a perspective view as viewed particularly from one end and from above; Figure 2 is a side elevation of one side of the device with the protective shield broken away to permit visual observation of the full side; Figure 3 is a side elevation of the opposite side of my device; Figure 4 is an end view of my device in a partially-closed and unlocked position; Figure 5 is a side elevation of the same side disclosed in Figure 3 with the locking member from the opposite face omitted for the purpose of greater clarity; Figure 6 is an end elevation of my device, otherwise similar to Figure 4 but with the device in closed and locked position; Figure 7 is a top plan view of the device in closed and locked position.

19 Referring with more particularity to the drawings:

20 A piece of metal, 1, preferably of spring steel or the like is stamped so as to form the locking elements and the pin elements hereafter more fully described; it is then suitably bent so as to provide a front or pin, face 2 and an opposing rear face 3, with edges 4 and 5. The material from which the opposing faces or sides 2 and 3 are formed is bent at 6 to provide a return bend or fold.

21 During the initial machining or stamping of the blank the upper end of the face or side 2 is partially cut away to provide a top edge 7, the height of which (from fold 6) is somewhat less than the height of a central, preferably curved, extension or locking nob 8. Desirably both outer corners or shoulders of the top edge 7 will be rounded to eliminate any sharp edges or corners. Struck out of the face 2 at the time of machining

the original blank are one or more pins 9 the outer ends of which may be thereafter, or originally, be sharpened as at 17 to give penetrating points. These pins 9 are bent upwardly and assume an approximately horizontal position at roughly ninety degrees (90°) from the plane of the face from which they were formed. The striking out and bending of the pins will leave corresponding openings 10 within face 2.

Turning now to the opposite face 2, at its upper end and at an elevation of approximately the same height as the elevation of face 2 when terminated by its upper edge 7, an extension of face 3 is folded over at right angles to 3 along edge 11 to form a top surface 12; the outer edge of top surface 12 is again folded over at right angles to form a lip or shield 13 which extends downwardly to a point below the sharpened ends of the pins 9. Prior to the folding operations and preferably at the time of initially stamping the blank a tongue 14 is struck out of that portion of the blank which ultimately forms face 3 and top 12. An opening 15 approximately centrally located in the tongue 14 is struck out in order to permit subsequent engagement with the extension 8 on face 2; the opening formed by striking out tongue 14 remains in face 3 and is of such a size and so positioned as to permit pins 9 to pass therethrough. It will be observed that tongue 14 remains as an extension of top surface 12 and is not folded along the edge 11 as is the remainder of top surface 12. Tongue 14 may be suitably formed into a curved rounded shape as shown in Figures 2 and 3, or it may be permitted to remain in a perfectly flat shape as shown in Figure 1. I prefer that the outer end of tongue 14 be curved so as to avoid any sharp edges or corners which might cause injury.

Mode of operation

When it is desired to use my device the opposing faces 2 and 3 are normally spread somewhat further apart than shown in Figure 4. One or more folds of material such as fabric or one or more sheets of paper may be inserted into the roughly U-shaped recess formed by face 3, lip 13, and top surface 12. When the material has been so placed, faces 2 and 3 are pressed together until the points 17 of the pins 9 extend through the opening 16 and penetrate the material to a point or degree at which points 7 of pins 9 approach lip 13 and which will permit tongue 14 to overlie face 2 and will also permit extension 8 to be inserted through opening 15, thereby locking the device through the cooperation of the locking means provided by 8, 14 and 15. When closed and locked the elements of my device will assume the position shown in Figure 6. When it is desired to open the device, faces 2 and 3 are passed together to permit tongue 14 to be elevated so as to free the element 8 from the engagement with opening 15, the faces 2 and 3 are spread apart, the fabric or material is disengaged from the pins 9 and withdrawn from the U-shaped opening formed by 3 and 13.

Equivalents

While I have described and illustrated my invention with reference to one modification thereof, certain other modifications may be employed without departing from the spirit of my invention. While I have described my device hereinabove with reference to a simple metallic stamping of, say spring steel, suitable alloys of other metals which will result in the desired resiliency may be utilized. Moreover, I may plate my base

metal with brass or with chromium or other corrosion-resistant elements or compounds, including, of course, precious metals such as silver or gold, or platinum. Instead of stamping out the pins 9 so as to leave the recesses 10 I may, if desired, use round pins which may be driven through, screwed into, riveted into or otherwise suitably affixed to the face 2. Such pins could, of course, be presharpened and would provide easier penetration of the fabric or material to be penetrated by them. Such an alternative arrangement would also permit more decoration on face 2 than could be added when the pins are stamped out of the face. In addition to desired decoration by plating or otherwise coating with metals, I may, of course, employ lacquers, enamels or plastics in order further to decorate and improve the appearance of the faces 2 and 3. I may also attach separate decorations to the outer surface of face 2.

I have referred above to the utilization of my pin or clip in fastening diapers on infants. I have also made a general reference to its use in fastening garments and neckties. In all such cases the features hereinabove described in detail provide a device which will permit one or more folds or sheets of material to be fastened together with firmness, due to the penetration of the pins through the folds or layers, with security due to the provision of the locking pins, and with safety due to the provision of the shield which definitely shields and prevents contact with the sharpened points of the pins. These same features and advantages could also be used when my device is adapted to a further use as a clothespin or suspension clip. Such use may readily be accomplished by providing a suitable ring which may be soldered or brazed or otherwise affixed along the fold 6. I have not illustrated such a ring in my drawings but contemplate its use where desired. When provided with such a ring my clip may also be used for hanging and drying of photographic negatives and prints, a use to which many prior art clips have been directed. In addition my clip may be used as an item of costume jewelry either in the form as shown in the attached drawings or with the addition of decoration, watches, compacts, purses or other items either to face 2 or by attachment to the aforementioned ring.

While I have illustrated my device in my drawings as possessing a pair of pins 9, I have contemplated that my clip may, if desired, be provided with three or more such pins. It may also be made with but a single pin.

I claim:

1. A safety clip adapted for repeated use in pinning pieces of paper or cloth, such as sheets, diapers, and the like, comprising two opposing resilient faces joined at a common extremity by a fold so as to form an approximately U-shaped recess, one of said faces having an extension at its upper end, said extension being bent outwardly and at an angle from said first face and being additionally bent downwardly to form a protective shield, spaced from and approximately parallel to said face, said one face also having an opening therethrough adjacent the upper end thereof, said other face having at least one pin connected to the inner surface thereof and at an angle thereto, said pin being so positioned as to be adapted to penetrate through the said opening in said first face and to be within the space covered by said protective shield and a locking device comprising a nob on said other face co-

operatively associated with a tongue connected to said upper extension on said first face said faces, said pin, said shield, and said locking device all being formed of and being an integral part of a single piece of metallic stock.

2. A safety clip adapted for repeated use in pinning pieces of paper or cloth, such as sheets, diapers, and the like, comprising a fastening clip formed from a single piece of stock material, comprising a pair of resilient opposed faces, at least one pin struck out of one of the said faces, an opening in the other of said faces adapted to permit passage of the outer end of said pin therethrough and said other face also having its upper end bent outwardly and downwardly to provide a shield for the extremity of said pin, and locking means formed at the upper edges of said two

faces said two faces, said pin, said shield, and said locking means all being formed of and being an integral part of a single piece of metallic stock.
